UNITED STATES PATENT OFFICE.

JOHN A. DRAIN, OF PHILADELPHIA, PENNSYLVANIA.

INGOT MOLD.

1,346,369.

Specification of Letters Patent. Patented July 13, 1920.

Application filed January 13, 1920. Serial No. 351,218.

To all whom it may concern:

Be it known that I, JOHN A. DRAIN, a citizen of the United States, residing in the city of Philadelphia, county of Philadelphia, and State of Pennsylvania, have invented certain Improvements in Ingot-Molds, of which the following is a specification.

This invention is an ingot mold having a lining of insulating material between its metal body and its exposed lining (as of fire brick), which makes contact with the metal, the insulating lining in its preferred form being more or less elastic.

The primary object of my invention is to provide a mold, which will hold the heat of the poured metal, secure more nearly even as well as slow cooling, effect substantial annealing and reduce the development of internal strains, segregation, crystallization, piping and "ingotism," together with the tendency to form ghosts, streaks and defects in ingots cast in molds heretofore used, particularly in forging ingots and large ingots generally.

In its preferred form, the cast metal body of the mold is made in sections so that a broken section can be replaced without entailing the expense of wholly replacing the mold, and the size of the mold can be varied by the removal or insertion of sections.

In the accompanying drawings, Figure 1 is a vertical sectional view of an ingot mold made in accordance with the invention, and Fig. 2 is a transverse sectional view of the same taken on the line 2^x—2^x of Fig. 1.

As illustrated in the drawings, the invention comprises a cast metal body having the bottom section 1 provided with the outer top flange 1^a together with the inner and outer bottom flanges 1^b and 1^c respectively, the intermediate section 2 having the outer flanges 2^a and 2^b at its respective ends, and the top section 3 having the outer bottom flange 3^a and the inner top flange 3^b, the respective flanges 2^a and 2^b registering with the flanges 1^a and 3^a to which they are connected by bolts 4 and 4^a.

A heat insulating lining 5 (preferably of elastic material) is constructed within the body next to the sections 1, 2 and 3 and between the flanges 1^b and 3^b; this lining being composed suitably of "cork" bricks 5^a, which are made of a formed and pressed mixture of cork and clay from which the cork has been burnt out, with the produc-

tion of a highly porous construction adapted for containing a relatively large body of air in its cells. But it will be understood that linings of other insulating materials, such as asbestos, may be substituted for the "cork" bricks.

A refractory lining 6, suitably of fire bricks 6^a, is constructed next to the inner lining 5 between the flanges 1^b and 3^b.

When hot metal is poured into a mold of this character, its heat is retained by the linings, particularly the inner lining of insulating material, so that it cools slowly and more evenly, with less variation in the dissipation of heat between the outer and inner strata. There is effected a distribution together with a reduction of the internal strains that are commonly developed, as well as a reduction in segregation, piping, crystallization and ingotism, while the ingot is annealed by the slow and more regular loss of its heat. When the inner lining is formed of elastic material that is perceptibly compressed by the metal poured in the mold, as in the case of a highly porous material containing a large amount of air, such lining will expand, due to the heat that it absorbs and the reduction of the pressure as the ingot shrinks in cooling, so that it will exert a useful following and continuing pressure on the sides of the ingot as it cools and shrinks.

The great difficulties and large losses in casting large forging ingots are greatly reduced in this manner, and highly desirable results are obtained in ingot casting generally as well as in casting various products that are benefited by slow and more regular cooling with consequent annealing.

The metal body of the mold is thus protected so that it is not subject to the extreme changes of temperature with resulting contraction and expansion by which it is frequently cracked and destroyed.

While the construction shown is designed for use as a complete mold, it may be used as a top for a mold having a bottom unprovided with an insulating lining so that the bottom of the ingot will be cooled more rapidly than the top in which the heat is held, or its dissipation retarded, to reduce the common defects therein.

Having described my invention, I claim:

- An ingot mold having a lining of refractory material and an inner lining of heat insulating material.

2. An ingot mold having an inner lining of elastic heat insulating material.
3. An ingot mold having a sectional metal body, a lining of fire brick and a lining of heat insulating material between the body and fire brick.
4. An ingot mold having an inner lining of "cork" bricks.
5. An ingot mold having a lining of fire brick and an inner heat insulating lining. 10
6. An ingot mold having an insulating lining containing air cells.

In testimony whereof I have hereunto set my hand, this 6th day of January, 1920,

JOHN A. DRAIN.
